PORTABLE BLEACHER

Donald E. Vance and Harold C. Vance,
Champaign, Ill.

Application September 3, 1938, Serial No. 228,423

5 Claims. (Cl. 189—2)

This invention relates to stands or bleachers, and more particularly to a portable structure of this kind.

An object of this invention is to provide a portable bleacher or grandstand which may be readily set up at a desirable location, the structure being of such a construction that additional units or sections may be readily coupled therewith so as to provide the desired size of stand or bleacher.

Another object of this invention is to provide a structure of this kind which may be readily taken apart in units so that the disassembled structure may be readily transported on trucks or like vehicles.

A further object of this invention is to provide a structure of this kind including an improved connecting or coupling means between adjacent units so as to securely lock the units together.

A still further object of this invention is to provide in a structure of this kind an improved connecting means between the several units which may be used not only to connect the several units together, but also to support foot boards.

Still another object of this invention is to provide a collapsible structure of this kind which comprises lightness in weight with strength so that the assembled stand will withstand the necessary stresses and weight.

With the foregoing and other object which may hereinafter appear, our invention consists of the novel construction, combination and arrangement of parts as will be more specifically referred to and as are illustrated in the accompanying drawings wherein is shown an embodiment of the invention, but it is to be understood that changes, variations and modifications may be resorted to which fall within the scope of the invention as claimed.

In the drawings:

Figure 1 is a detail end elevation of a pair of stand sections constructed according to an embodiment of this invention.

Figure 2 is a fragmentary rear elevation of the stand.

Figure 3 is a rear elevation of one of the supporting units for one of the stand sections.

Figure 4 is a perspective view of one of the stand sections partly broken away showing the manner of assembling the several units comprising a stand section.

Figure 5 is an enlarged fragmentary end elevation of a pair of units showing the manner of coupling or connecting the units together.

Figure 6 is a sectional view taken on the line 6—6 of Figure 5.

Figure 7 is an enlarged sectional view taken on the line 7—7 of Figure 5.

Figure 8 is a detail end elevation of one of the connecting members for the units.

Figure 9 is a detail end elevation of the opposite end of the connecting unit shown in Figure 8.

10 Figure 10 is an enlarged fragmentary sectional view taken on the line 10—10 of Figure 6.

Figure 11 is a fragmentary front elevation of one of the posts.

Figure 12 is a detail front elevation partly broken away of one of the supporting posts.

15 Figure 13 is a sectional view taken on the line 13—13 of Figure 12.

Figure 14 is a sectional view taken on the line 14—14 of Figure 13.

20 Figure 15 is a detail end elevation of one of the seat supporting members secured to a supporting post, and

Figure 16 is a fragmentary top plan of the connecting means between the base positions of adjacent stand sections.

25 Referring to the drawings and first to Figure 1, the numeral 20 designates generally one stand section, and the numeral 21 designates a second stand section constructed according to the embodiment of this invention. The stand section

30 20 is a lower or smaller stand section which has the seats thereof increasing in height toward the rear, and the stand section 21 has the lowermost seat thereof elevated above the uppermost seat of the front stand section 20, and the succeeding seats in the stand section 21 rise in regular order.

35 The stand section 20 is constructed of a plurality of units each supported on a pair of base or supporting members 22. These base members 22 are constructed preferably of a flat board of suitable thickness and each base member 22 has secured to the upper surface thereof an elongated angle bar 23 which is secured as by bolts 24 or the like. The angle bar 23 has one leg thereof vertical, and this vertical leg 25 is provided with a plurality of longitudinal spaced apart slots 26 which open through the upper edge of the vertical flange or leg 25.

40 The supporting units each comprise a pair of upright posts 27 which are fixedly connected together by means of a pair of crossed bracing members 28 and 29. The opposite ends of the bracing members 28 and 29 may be welded or otherwise fixedly secured to a side of the posts 55 27.

The posts 27 are constructed in channel or U-shaped form as shown in Figure 6, and the bracing members 28 and 29 are secured to the web or bight 48 of the channel member 27. Each channel member 27 is provided, adjacent the lower end thereof with a bolt 30 provided with a head 31 which is spaced from one leg or side of the channel member 27 and each bolt 30 is preferably welded or otherwise fixed to the opposite sides or legs of a channel member 27.

The vertical flange 25 of the angle bar 23 is adapted to engage between the head 31 and the adjacent side of a post 27 as shown in Figure 12. The upper end of each post 27 has fixedly secured thereto a right angularly disposed angle bar 32 which has a vertical leg 33 fixed as by welding or the like to one side of the post 27, and the other leg 34 is horizontal and overlies the top of the post 27. The angle member 32 comprises a seat supporting means which is fixed to the top of the post 27 and each supporting member 32 is provided at the opposite ends thereof with upwardly projecting lugs or plates 35.

A channeled seat board supporting member 36 is adapted to engage on the upper or horizontal leg 34 of the angle member 32, and the abutting ends of a pair of seat boards 37 are adapted to engage in the channel member 36 as shown in Figure 12. In this manner the seat supporting boards 37 at their abutting ends will not overlap each other as is the case with stand structures at present available.

The bottom wall 38 of the channel member 36 is provided with a downwardly offset tongue 39 engaging beneath the horizontal flange 34 of the angle member 32, and in order to provide a relatively tight fit each angle member 32 is provided with an insert 40 which is secured to the underside of the flange 34 at substantially the longitudinal center thereof.

The channel member 36 is adapted to engage between each pair of upwardly extending lugs 35 so that the channel member 36 will be held against lateral movement on top of each post 27. The end channel members 36 are provided with upwardly extending portions 65 engageable with the ends of the foot boards 56 to hold the foot boards 56 against endwise movement.

The foremost or lowermost post 27 is supported in vertical position or at right angles relative to the base bar 23 by means of a brace 41 which is bolted at its upper end as at 42 to the post 27. The lower end of the brace 41 is bolted as at 43 to the vertical flange 25 of the angle bar 23 adjacent the forward end of the angle bar 23. A preceding unit comprising a pair of posts 27 and bracing members 28 and 29 is held in a vertical position and connected to a succeeding unit by means of a pair of horizontally disposed connecting bars 44 which also serve the purpose of supporting foot boards 56 below the seat boards 37.

The combined connecting bars and foot board supporting members 44 are constructed in channel or U-shaped form as shown in Figures 8 and 9, and one end of the channel bar 44 has fixedly secured thereto a right angularly disposed bar 45 which extends above and below the bar 44. The rear side of a preceding post 27 is provided with a U-shaped saddle member 46 which has the parallel legs thereof welded or otherwise fixedly secured to the outer sides of the parallel legs of the post 27.

The bight 47 of the saddle member 46 is positioned in spaced relation to the bight 48 of the post 27 so that the downwardly projecting portion 49 of the bar 45 may engage in the pocket 50 formed between the bights 47 and 48. The upwardly projecting portion 51 of the bar 45 is adapted to engage flat against the bight 48 of the post 27 so as to hold the bar 44 against movement in one direction relative to the part 27 while the lower projecting post 49 holds the bar 44 against movement relative to the post 27 in the opposite direction.

The open side of a post 27 of a succeeding unit is provided with a plate 52 which engages against the legs of the post 27 being welded or otherwise fixedly secured thereto with the upper edge thereof of substantially coplanar with the upper edge of the saddle 46 so that the connecting bar 44 will be disposed in substantially a horizontal position and with the open side or parallel legs of the connecting bar 44 resting on the upper edge of the saddle 46 and the plate 52.

The connecting bar 44 has a coupling member 53 at the opposite end thereof which is constructed in the form of a square tubular member secured as by welding or the like to the adjacent end of the connecting bar 44. This coupling member 53 is adapted to engage between the parallel sides or legs of the post 27 inwardly of the plate 52 as shown in Figure 10. A bolt 54 is threaded through the bight 48 of the post 27 and contacts with the depending member 53 so as to hold this member 53 against vertical movement interiorly of the post 27. A lock nut 55 is threaded onto the bolt 54 and provides a means for locking the bolt 54 against rotation after it has been tightened to the desired degree.

The connecting bars 44 are adapted to have one or more foot boards 56 secured thereto as by bolts 57. In the present instance there are two of such foot boards 56, but it will be understood that one or more of such boards may be used. The foot boards 56 also provide a means for holding the connecting bars against separation and provide an additional means for strengthening the stand structure.

The stand section 21 is constructed of supporting units 27, 28, and 29 similar to the stand section 20, but the posts 27 of the section 21 are considerably higher or longer, and in order to provide a means whereby the posts 27 of the stand section 21 may be held against tilting forward or backward we have provided a plurality of crossed bracing members 58 and 59. These bracing members 58 and 59 are bolted or otherwise secured at their intersecting portions by means of a rivet or bolt 60, and the opposite ends of the bracing members 58 and 59 are secured to the posts 27 by means of bolts 61.

In practice these bracing members 58 and 59 are of such length as to extend between at least three posts 27 with the intermediate post at the crossing of braces 58 and 59 so that if desired, the bolt 60 may also be extended through the intermediate post 27 as shown in Figure 1. The first bracing means comprising the two braces 58 and 59 connect the rearmost posts 27 of the front section 20 with the adjacent posts 27 of the rear section 21.

The front section 20 is not shown as having any bracing members similar to 58 and 59 which brace the stand against forward and rearward stresses, other than the front bracing member 41. However, if desired, the units comprising the

front section 20 may be suitably braced by bracing members similar to 58 and 59.

The two sections 20 and 21 are tied together at their bases by means of a looped strap or clevis 62 which is bolted or otherwise fixed to one of the base members 22 and this loop or clevis 62 is adapted to engage over a hook 63 carried by a succeeding base member 22. The coupling between a preceding and a succeeding base member 22 is relatively loose so that the desired connection may be made between the front section 20 and the rear section 21 by means of the connecting bars 44.

In the assembling of this stand structure, the base members or sills 22 are laid flat on the ground in parallel relation and in the present instance four of these sills or base members 22 are used for each section 20 and 21. The sections 20 and 21 have a length substantially equal to the length of the seat boards 31 and the foot boards 56. It will be understood, however, that other sections 20 may be disposed in end abutting relation so as to provide the desired length of stand in addition to the desired depth, which depth is accomplished by coupling a section 21 to a section 20. With the base members 22 having the angle bars 23 secured thereto, positioned in substantially the same horizontal plane, each aligned pair of base members 22 are connected together by means of the clevis 62 and the hook 63.

The foremost unit comprising a pair of posts 27 and bracing members 28 and 29 is firmly secured to a pair of base members by means of the bracing members 41, and with the foremost unit in position, a succeeding unit is engaged with the base members 22 and 23 and then a pair of connecting bars 44 are intercoupled with the preceding and succeeding units with the depending coupling member 53 engaging in the forward open side of a succeeding post 27 and with the forward coupling member 45 engaging a saddle 46 of a preceding post.

In Figure 4 there is shown the manner of assembling the stand structure wherein the front portions of the section 20 are already assembled, and the rear units of this section are in a position for coupling the succeeding units. It will be noted that the succeeding units each have the connecting bars 44 secured thereto by means of the locking members 54 after which the units are rocked forwardly with the bolt 30 engaged in a slot 26 of the angle member 23. It will be understood that in order to snugly couple the coupling member 45 it may be necessary to slightly raise the succeeding unit in the slot 26 so that the depending part 49 of the coupling member 45 may readily engage in the pocket 50.

The lower ends of the bracing members 58 and 59 are adapted to engage the extended or threaded portion of the bolt 30 as shown in Figure 12, and a nut 64 is threaded onto the bolt 30 so as to tightly hold the bracing members 58 and 59 at their lower ends onto the posts 27.

A stand or bleacher constructed according to this invention can be manufactured at a relatively small cost, and can be erected with the use of a minimum amount of labor and when erected will safely hold persons up to the capacity of each section in a comfortable manner. After the use for which the stand has been erected has passed, the stand can be collapsed by uncoupling the several units as hereinbefore described. A stand constructed according to this invention embodies the use of a relatively small

number of small parts so that such small parts will not readily become lost during the transportation of the collapsed stand or during the erecting or dismantling of the stand.

5. What we claim is:

1. In a portable stand structure of that type including parallel spaced sets of spaced parallel uprights carrying seat board supports, the combination of sets of horizontally disposed spaced yokes integral with and extending rearwardly from each of the said uprights other than the rearmost uprights, a support secured to the forward face of each of the said uprights other than the foremost uprights, foot board supporting members arranged between the uprights of each set and removably mounted on said yokes and supports, said members having vertically extending means at their forward ends bearing against the rear faces of the uprights other than the rearmost uprights and extending downwardly through said yokes, said members having vertically extending means at their rear ends arranged in the uprights having connected thereto said supports and disposed rearwardly of the latter, and forwardly and rearwardly adjustable clamping structures connected to the uprights other than the foremost uprights, correlating with the vertically extending means at the rear ends of said members to provide when adjusted forwardly for detachably clamping said members to the uprights.

2. In a portable stand structure of that type including spaced parallel uprights of forwardly opening channel like form and seat boards connected with the upper ends of said uprights, the combination of spaced sets of spaced foot rest board supporting elements, the elements of each set being arranged between the uprights of a set, a horizontally disposed yoke-shaped front support secured to the sides of each upright of a set other than the rear upright of the set, the bights of said supports being spaced from the rear faces of those uprights to which the supports are secured, rear supports secured to and disposed transversely of the front faces of each upright of a set other than the front upright of the set, each of said elements being mounted at its ends on a front and a rear support, each of said elements having a bar at its forward end extending into the front support and a coupling member at its rear end arranged in an upright rearwardly of the rear support secured to the latter, and clamping means carried by the uprights of a set to which the rear supports are secured and engaging said coupling members for detachably clamping the elements to the uprights.

3. In a portable stand structure of that type including a seat board and an upright, the combination of an angle-shaped support including respectively a vertical leg having its forward face secured intermediate its ends to one side face of the upright and a horizontal leg arranged over and spaced from the top of the upright, an insert secured to the lower face of said horizontal leg, and a seat board support positioned on and transversely of said horizontal leg and formed on its bottom with an offset tongue lengthwise thereof bearing against the lower face of said insert for detachably connecting said seat board support with said upright.

4. The invention as set forth by claim 3 having combined therewith a pair of vertically disposed lugs, each secured to an edge part of said legs,

flush with the rear face of the vertical leg and extending above the horizontal leg.

5. In a portable stand structure of that type including seat and foot boards, a supporting structure for said boards comprising the combination of a set of spaced parallel flat base members, parallel angle-shaped bars each formed of a horizontal leg and a vertical leg, said horizontal legs disposed upon and lengthwise of the upper faces of said members, countersunk means for detachably securing said horizontal legs to said members, said vertical legs being formed with spaced notches opening at their upper edges, spaced sets of spaced forwardly opening chan-

nelled uprights having said boards connected therewith, each set of uprights mounted on a horizontal leg and bearing against the forward face of a vertical leg, spaced sets of upstanding oppositely disposed inclined bracing elements, means for securing the upper ends of said elements to certain of said uprights, holdfast means extending through said notches connecting the lower ends of said uprights to said vertical legs, and certain of said holdfast devices detachably connecting the lower ends of said elements to the said certain of said uprights.
